UNITED STATES PATENT OFFICE.

CARL E. MORDE, OF NEW BEDFORD, MASSACHUSETTS, ASSIGNOR TO THE PAIRPOINT CORPORATION, OF NEW BEDFORD, MASSACHUSETTS.

DESIGN FOR A GLASS VESSEL.

No. 40,079.

Specification for Design.

Patented June 22, 1909.

Application filed April 26, 1909. Serial No. 492,432. Term of patent 7 years.

To all whom it may concern:

Be it known that I, CARL E. MORDE, a citizen of the United States, residing at New Bedford, in the county of Bristol and State of Massachusetts, have invented a new, original, and ornamental Design for a Glass Vessel, of which the following is a specification, reference being had to the accompanying drawing, forming part thereof.

The figure is an elevation showing my new design.

The design resides in the glass vessel ornamented, as shown in the drawing with a

combination of leaves and stalks, and flowers. The larger leaves A are deeply cut as shown at a, a. Branching from the stem of the larger leaves are small anemone shaped flowers b, b, and leaf stalks c, c.

I claim—

The ornamental design for a glass vessel, as shown and described.

CARL E. MORDE.
